Primary Examiner — Darcey E Gottschalk(74) Attorney, Agent, or Firm — Malloy & Malloy, P.L.(57) CLAIM

The ornamental design for a bottle with wings and a ring, as shown and described.

DESCRIPTION

FIG. 1 is a front perspective view illustrating my design for a bottle with wings and a ring;

FIG. 2 is a front view thereof;

FIG. 3 is a left side view thereof;

FIG. 4 is a top view thereof;

FIG. 5 is a right view thereof;

FIG. 6 is a bottom view thereof; and,

FIG. 7 is a rear view thereof.

The broken lines in the drawings are included for purposes of illustrating portions of the bottle with wings and a ring, that form no part of the claimed design.

1 Claim, 7 Drawing Sheets(56)
